UNITED STATES PATENT OFFICE.

JOHN L. ECKERSON, OF NEW YORK, N. Y.

DISPLAY-CABINET.

1,251,196.

Specification of Letters Patent. Patented Dec. 25, 1917.

Application filed May 19, 1917. Serial No. 169,741.

To all whom it may concern:

Be it known that I, JOHN L. ECKERSON, a citizen of the United States, residing at New York, in the county of New York and 5 State of New York, have invented certain new and useful Improvements in Display-Cabinets, of which the following is a specification.

This invention relates to display devices, 10 particularly to display cabinets for umbrellas, canes, wearing apparel and other articles of merchandise, and has for its object the provision of a display cabinet having a glass covered front portion and a plurality of revoluble shelves disposed therein and so associated with the back portion that opening a door in the back portion will cause the shelves to be withdrawn from the cabinet for the removal of articles displayed, the 20 shelves being returned when the door is closed.

An important object is the provision of a cabinet of this character having its back portion so constructed that it may be swung bodily open to permit ready access to the 25 interior without removing the shelves, the shelves being revoluble within the frame of the cabinet and detachably connected with the operating door.

30 A further object is the provision of a cabinet of this character having a novel pivotal mounting for the shelves whereby they will swing clear of the edges of the operating door and the normally stationary back portion.

35 Another object is the provision of a cabinet of this character which will be dust-proof, simple in construction and operation, pleasing in appearance, efficient in 40 service and a general improvement of the art.

With these objects and advantages in view, my invention consists in the novel construction and arrangement of parts to be 45 hereinafter more fully described and claimed, and illustrated in the accompanying drawings, in which:

Figure 1 is a rear elevation of the cabinet,
Fig. 2 is a similar view with the operating 50 door opened,

Fig. 3 is a cross-sectional view through the cabinet closed,

Fig. 4 is a similar view with the operating door opened,

Fig. 5 is a similar view with the entire 55 back opened and disconnected from the shelves, and

Fig. 6 is a fragmentary perspective view 60 showing the pivotal mounting of the shelves in detail.

Referring more particularly to the drawing, the numeral 1 designates a base upon which are mounted uprights 2 connected at their upper ends by a cross-bar 3. These parts form the frame of the cabinet. Glass 65 sides 4 and front 5 are secured to this frame and to each other in any suitable manner. Pivotaly connected with one upright 2 by 70 hinges 6 is the normally stationary section 7 of the back to which is pivotally secured by hinges 8 the operating door 9. The section 7 is provided with a suitable lock 10 and the door 9 is provided with a similar lock 11 and also a handle 12.

The revoluble shelf member comprises a 75 vertically disposed standard 13 having secured thereto at suitable intervals trays or shelves 14 and 15 of any convenient size and shape and adapted to support any desired articles to be displayed, though in the present instance I have shown them as semi-circular and provided with holes for the reception of umbrellas, parasols or canes. The shelves 14 are shown as of less diameter 80 than the shelves 15 and in alinement with each other and arranged alternately in relation to the shelves 15, though I do not limit myself to this arrangement.

This shelf member is revolubly mounted 85 within the frame of the cabinet by means of 90 L-shaped brackets 16 secured to the upper and lower ends of the standard 13 and having pivot pins 17 secured to the outwardly extending arms 18 thereof and disposed in suitable socket or bearing members 19 in the 95 base 1 and cross-bar 3.

It is necessary that the shelf member be 100 detachably connected with the operating door 9, and to this end any suitable fastener such as a hook 20 may be provided upon one of the shelves for engagement with a screw-eye 21 on the door 9. It will be understood 105 that I may use some preferred form of catch in place of this hook and eye connection.

In order that the back section 7 and door 9 may fit snugly within the frame and still not interfere with the brackets 16, I provide them with notches or recesses 22 and

23, respectively, for the reception of the brackets.

When the cabinet is in use for displaying articles, the door 9 is of course closed, and the parts are as shown in Figs. 1 and 3. When it is desired to remove an article from the cabinet, the door 9 is swung open, whereupon the shelf member will be rotated upon the pivot pins 17, and will swing outwardly 10 with the door into the position shown in Figs. 2 and 4. The brackets 16 constitute an eccentric pivotal mounting so that the standard 13 will clear the edges of the door 9 and the back section 7 and permit the shelves to be disposed outwardly of the cabinet and against the door 9. When it is desired to gain access to the interior of the cabinet for cleaning it or for any other purpose, the door 9 is partially opened and the hook 20 disengaged from the eye 21, whereupon the door 9 and the back section 7 may be swung bodily on the hinges 6 into the position shown in Fig. 5, it being understood that the locks 10 and 11 be open during this 25 operation.

From the foregoing description and a study of the drawing, it will be apparent that I have thus provided a display cabinet which is simple, inexpensive, easily operated, 30 dust-proof and efficient in every way.

It will be readily understood that I reserve the right to make such changes in the form, construction and arrangement of parts as will not depart from the spirit of the invention and such as will fall within the 35 scope of the claims.

Having thus described my invention, I claim:

1. A display cabinet comprising a casing, 40 a back section connected therewith, a door hinged to said back section, a standard within said casing, shelves secured to said standard and connected with said door, and means for pivoting said standard within said casing whereby said standard may be rotated 45 clear of the hinged edge of said door when said door is opened with said shelves dis-

posed outwardly of the casing and against said door.

2. A display cabinet comprising a casing, 50 a back section hingedly connected with one side edge and extending half way across the back thereof, a door hinged upon the free edge of said back section and coöperating therewith to close the back of said casing, 55 a standard pivoted within said casing, and shelves on said standard, one shelf being detachably connected with said door whereby said door and said back section may be swung open, and said standard and shelves 60 being rotatable to permit access to said casing at either side of said standard.

3. A display cabinet comprising a casing, a back section connected therewith, a door hinged to said back section, a standard with 65 in said casing adjacent said door, shelves carried by said standard, angular brackets secured upon the ends of said standard and having offset portions pivotally connected with in said casing, whereby said standard may 70 be rotated clear of the hinged edge of said door when the door is opened, with said shelves disposed outwardly of the casing against said door, and means connecting one 75 of said shelves with said door.

4. A display cabinet comprising a casing, a back section hingedly connected therewith, a door hinged to said back section, a standard within said casing adjacent said door, shelves carried by said standard, one of said shelves being detachably connected with said door, and L-shaped brackets secured upon the ends of said standard and having their outwardly extending arms pivotally connected with said casing in alignment with the 85 hinges of the door whereby said standard may be rotated clear of the hinged edge of said door and said back section when the door is opened to permit said shelves to be disposed outwardly of the casing against 90 said door.

In testimony whereof I hereto affix my signature.

JOHN L. ECKERSON.
